UNITED STATES PATENT OFFICE

RICHARD O. PFEIFFER, OF NEWARK, NEW JERSEY

ELECTRIC LIGHTING FIXTURE

Application filed June 25, 1930. Serial No. 463,590.

This invention relates to ceiling fixtures designed for use in tunnels, low passages, vestibules, and rooms with limited ceiling height where it is necessary that the fixture does not project far below the surface of the ceiling.

Heretofore, fixtures of the class herein described have been provided with rectangular face plates forming a part of a heavy metal housing positioned in a recess in the ceiling. Such fixtures are objectionable in that the rectangular shape of the face plates renders it difficult to properly align a number of fixtures on a ceiling, and the general structure of the fixture has necessitated specially constructed outlet boxes.

It is an object of this invention to provide a ceiling fixture having a circular face plate substantially flush with the surface of the ceiling, the fixture being adapted to fit any standard outlet box.

Inasmuch as it is often necessary in certain places, such as motion picture theaters, to provide a dim light, it is a further object to provide a ceiling fixture having a bright light and a dim light operated on independent circuits.

These and other advantageous objects are attained by the novel construction, combination and arrangement of parts hereinafter described and shown in the accompanying drawings, constituting a material part of this disclosure and in which:

Figure 1 represents a sectional view of the device.

Figure 2 represents a bottom view of the fixture.

Figure 3 represents a plan view of the device.

Referring to the drawings, the fixture is shown to include a reflector 3, having a neck provided with an enlarged rounded edge 4, cooperating with a groove or thread in an externally grooved or threaded cap 5, whereby the cap 5 removably receives the rounded edge 4 of the reflector 3, the cap having a central aperture 7.

A neck 6 is in threaded engagement with the cap 5, and has an inwardly projecting flange 8 to which is attached a plate 9. The

neck 6 has also an outwardly projecting flange 10, secured by bolts 11 to a standard outlet box 12, the latter being attached to a joist or other suitable means, and has an aperture through which passes a tube 13 carrying a plurality of conductors, one of the conductors passing through a rigid pipe 14 threaded into the plate 9, while the other conductors are carried by the flexible tubing 15 and 16, the pipe and tubing supporting respectively the sockets 17' and 17.

The fixture is provided with a face plate 18, made preferably of brass, bronze or copper, and it is fastened directly to the ceiling by means of screws 26 or any other suitable means, such as toggle bolts, (not shown) surrounded by bushings 24.

An angle 19 is attached to the face plate 18, and passes through an aperture therein to provide a support for a screw 20, which fastens in place the circular angle 21 which forms a frame supporting a guard comprising a plurality of bars 22 radiating from a centrally positioned ring 26', and riveted thereto. When the fixture is used in gymnasiums, etc., the protective guard is desirable.

The face plate 18 has an inturned flange 23 cooperating with the angle 21, and the angle 21 is connected to the face plate by means of a hinge 25.

In assembling the fixture, the neck 6 is screwed onto the cap 5, the plate 9 having previously been attached to the inwardly projecting flange 8 of the neck 6, as shown in Figure 3.

The conductors passing through the tube 13 are then passed through the pipe 14 and the flexible tubing 15 and 16, the flexible tubing and pipe being secured to the plate 9. The fixture is then attached to the outlet box 12 by means of bolts 11 passing through the outwardly projecting flange 10 on the neck 6.

The face plate 18 together with the guard and angle frame 21 are then secured in place on the ceiling, and since the face plate 18 and its associated parts are circular in shape, it is obvious that there will be no difficulty in aligning a plurality of such fixtures on a ceiling.

The sockets 17 carry incandescent lamps of very low candle power, while the lamp carried by sockets 17' is very strong. The lamp carried by socket 17' is designed for general illumination, while the lamps carried by socket 17 are intended for use only when a dim light is required. The sockets 17 and the socket 17' are on different circuits so that the lamps may be lighted independently of each other.

This arrangement of the lamps is very advantageous in motion picture theaters in which a dim light is required at all times. During the showing of the motion picture, the lamps in sockets 17 would be lighted, to provide a dim light, and at the completion of the picture the lamp in socket 17' would be lighted to give a brilliant illumination in order to enable persons to properly leave their seats in the theater.

By means of the flexible tubes 15 and 16, sockets 17 may be moved to various positions with relation to socket 17', thus enabling a variety of effects.

It is obvious that the plate 9 may be used for one socket only, that is, the socket 17' and the flexible tubes 15 and 16, and sockets 17 may be dispensed with.

While the cover has been described provided with a guard, it is clear that a glass may be substituted for the guard when so desired.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a ceiling fixture, a reflector provided with a small neck portion having a rounded edge, an apertured cap having a grooved portion removably receiving the rounded edge of said reflector, a neck in threaded engagement with the cap, an inwardly projecting flange on said neck, a plate secured to the underside of said flange, a rigid pipe and a pair of flexible tubes attached to the plate, and an outwardly extending flange on the neck by means of which the fixture may be attached to a standard outlet box.

2. In a ceiling fixture, a reflector having an open top, a neck detachably secured to the reflector, a plate supported by said neck, a rigid conduit carried by said plate and normally passing through the center of the open top of the reflector, and a pair of flexible socket carrying conduits supported by the plate and normally extending into the reflector adjacent the wall thereof, adapted to be manipulated into position adjacent the

rigid conduit so that the open top of the reflector may be readily drawn thereover to remove the reflector.

3. In a ceiling fixture, a reflector, having its lower edge substantially flush with the surface of the ceiling, a circular face plate surrounding the reflector and attached to the surface of the ceiling, and an angled cover hinged to the face plate, said cover having a plurality of spaced bars extending to a centrally positioned ring to form a guard, and a latch extending from the face plate and adapted to have latching engagement with the angled cover.

4. In a ceiling fixture, a reflector provided with a small neck portion having an inwardly directed, rounded edge, an apertured cap having a grooved portion removably receiving the rounded edge of said reflector, and a neck in threaded engagement with the cap, the lower end of said neck bearing against the neck portion of the reflector.

This specification signed this 24th day of June, 1930.

RICHARD O. PFEIFFER.
